UNITED STATES PATENT OFFICE.

MAURICE WILLIAM SMITH, OF LYNDHURST, HODDESDON, ENGLAND.

QUICK-RELEASE BENCH-VISE.

1,391,913.

Specification of Letters Patent. Patented Sept. 27, 1921.

Application filed May 7, 1920. Serial No. 379,472.

(GRANTED UNDER THE PROVISIONS OF THE ACT OF MARCH 3, 1921, 41 STAT. L., 1313.)

To all whom it may concern:

Be it known that I, MAURICE WILLIAM SMITH, of Lyndhurst, Hoddesdon, in the county of Herts, England, a subject of the

5 King of Great Britain and Ireland, have invented certain new and useful Improvements in or Relating to Quick-Release Bench-Vises, (for which I have filed applications in England October 24, 1918, No. 10 130,517, in France April 1, 1920, and in Belgium April 8, 1920,) of which the following is a specification.

This invention relates to quick release bench vises, and comprises a fixed jaw in 15 which are mounted two half nuts, a movable jaw formed integral with a double sliding bar sliding in the fixed jaw, a clamping screw disposed between the two members of the double sliding bar, means for opening 20 and closing the half nuts from and into engagement with the clamping screw and means for retaining the half nuts in their closed position.

The object of this invention is to provide 25 an improved form of quick release bench vise of this type.

A quick release bench vise made in accordance with this invention comprises two half nuts carrying pins working in inclined slots 30 in two sliding members, the said sliding members being adapted to move simultaneously and in opposite directions. The inclined slots in the sliding members are formed for a portion of their length at one 35 end parallel to the sliding face of the members to retain the half nuts in engagement with the screw.

Referring to the drawings filed here- 40 with:—

Figure 1 is an elevation of one form of vise made in accordance with this invention;

Fig. 2 is a sectional plan of the fixed jaw;

Fig. 3 is a cross section of the fixed jaw 45 showing the half nuts engaging the clamping screw;

Fig. 4 is a cross section showing the half nuts clear of the clamping screw.

The jaw *a* of the vise is adapted to be secured to a bench by screws or bolts through 50 the holes *b* *b*. Within a housing *c* in the jaw *a* are disposed two half nuts *d* *d*'. Each half nut is connected to a bar *e* *e*' by a pin *f* *f*' passing through inclined slots *g* *g*' in the bars *e* *e*' the bars *e* *e*' working in

a vertical slot in the half nuts. The slots 55 *g* *g*' are provided with parallel or notched ends *g* *g*' to lock the half nuts when in position.

The slots *g* *g*' are parallel to one another but inclined to the sliding face of the bars 60 *e* *e*' except at their ends *g* *g*' where they are parallel to the sliding face of the bars *e* *e*'.

Any force, therefore, tending to open the two half nuts presses the pins *f* *f*' onto these 65 parallel parts *g* *g*' and would have no tendency to move the sliding bars *e* *e*' as would be the case if these slots were inclined for their whole length.

The movable jaw *h* is provided with a 70 double sliding bar *j* *j*, and between the sliding bars is a clamping screw *k* adapted to be rotated by a handle *m*. Below the lower sliding bar is a square shaft *n* on which is mounted a handle *o* and a two arm lever 75 *p* *p*' provided with slots *r* *r*'. The lever *p* *p*' is connected to the bars *e* *e*' by pins *s* *s*' which pass through the slots, the half nuts *d* *d*' are adapted to engage the clamping screw *k*, and are kept normally engaged 80 with the screw by a coil spring *t*. When it is desired to move the loose jaw *h* without the operation of screwing the handle, the squared shaft *n* is rotated by the handle *o* raising the bar *e*' and lowering the bar *e*, 85 the pins *f* *f*' traveling in the inclined slots *g* *g*' throwing the half nuts out of engagement with the screw *k* so that the jaw can be moved forward or backward at will. On 90 releasing the handle *o* the half nuts immediately engage the screw *k* by the action of the spring *t*.

With the vise made in accordance with this invention, the width occupied by the sliding member is comparatively narrow, 95 thus allowing plenty of room on each side of the bar with a normal width of jaw.

What I claim and desire to secure by Letters Patent is:—

1. A quick release vise comprising a fixed 100 jaw adapted to be attached to a bench, two half nuts mounted in said fixed jaw, a double sliding bar, a movable jaw carried by said double sliding bar, said double sliding bar being adapted to slide in said fixed jaw, a clamping screw operating between said half nuts, means for opening and closing said half nuts, said means comprising 105

vertical slots in said half nuts, pins carried by said half nuts, sliding members adapted to move simultaneously and in opposite directions and to operate in said vertical slots in said half nuts, inclined slots in said sliding members adapted to coact with the said pins carried by said half nuts, a square shaft disposed parallel with said double sliding bar, a two arm lever on said square shaft, slots formed in said two arm lever, pins on said sliding members, coacting with said slots in the two arm lever, a handle on said square shaft, and means for retaining the said half nuts in their closed position.

15 2. A quick release vise comprising a fixed jaw adapted to be attached to a bench, two half nuts mounted in said fixed jaw, a double sliding bar, a movable jaw carried by said double sliding bar, said double sliding bar being adapted to slide in the said fixed jaw, a clamping screw operating between said half nuts, means for opening and closing said half nuts, said means comprising vertical slots in said half nuts, pins

carried by said half nuts, sliding members adapted to move simultaneously and in opposite directions, and to operate in said vertical slots in said half nuts, inclined slots in said sliding members adapted to coact with the said pins carried by said half nuts, a square shaft disposed parallel with said double sliding bar, a two arm lever on said square shaft, slots formed in said two arm lever, pins on said sliding members, coacting with said slots in the two arm lever, a handle on said square shaft, and means for retaining the said half nuts in their closed position, said retaining means characterized in that the slots in said sliding members are formed parallel for a portion of their length at one end to the sliding faces of said sliding members, and a spring suitably disposed on said square shaft whereby the sliding members are retained in the locking position.

20 In testimony whereof I have signed my name to this specification.

MAURICE WILLIAM SMITH.
